UNITED STATES PATENT OFFICE.

HAROLD L. WATSON, OF LYNN, MASSACHUSETTS, ASSIGNOR TO GENERAL ELECTRIC COMPANY, A CORPORATION OF NEW YORK.

ELECTRIC FURNACE.

Application filed November 13, 1898. Serial No. 148,169.

My invention relates to electric furnaces, more particularly to high temperature electric furnaces and has for its object the provision of a simple, reliable and efficient high temperature electric furnace.

More specifically my invention relates to an electric furnace of the resistor type which is capable of maintaining a temperature sufficiently high for the fusion and treatment of the more refractory metals and compounds. The furnace may be successively used with temperatures as high as 1900° to 2000° C., and it is especially useful in the fusing of large masses of quartz.

For a more complete understanding of my invention reference should be had to the accompanying drawings in which Fig. 1 is a vertical sectional view of an electric furnace embodying my invention, Fig. 2 is a plan view of the device shown in Fig. 1, Fig. 3 is a view showing details of construction, while Fig. 4 shows a modified form of electrical connections.

Referring to the drawings, my invention in one form comprises a heating chamber 10 which is defined by walls made of heat refractory material, a charging opening 11 being provided in the bottom wall. The side and bottom walls of the heating chamber are preferably lined with re-crystallized carborundum bricks 12, although any sufficiently heat refractory material which will be inert in the carbonaceous-silicious atmosphere prevailing in fusing quartz may be used. Such other materials which might be used under certain conditions are alumina, zirconia and thoria. The top of the furnace chamber may be formed of similar bricks or, as shown in the drawing, it may be formed of graphite slabs 13 over which is placed a layer of silica sand 14. The recrystallized carborundum bricks forming the side and bottom walls are heat insulated by means of a layer of zirconium silicate bricks 15 outside of which are two layers 16 of fire brick.

This furnace structure rests on a metallic supporting plate 17 having a central aperture 18 registering with the bottom opening 11. The plate 17 rests on brick piers 19 and 20 on which the furnace structure is supported at a sufficient height for convenience in charging. A steel framework 21 is provided around the entire structure to facilitate the operation of a platform 22 on which the charge is placed. This platform comprises

a metallic support 23 which rests on parallel cross bars 24 and 25 extending between the piers 19 and 20 and having their ends connected by vertical rods 26 to the ends of an elevated frame 27 above the furnace. This frame is free to move in a vertical direction between guides 28 and 29 and as shown may be raised and lowered to raise and lower the platform 23 by means of a chain hoist or crane 30. A bottom wall 31 made of successive layers of heat refractory and heat insulating bricks similar to the structure of the stationary walls is provided on the support 23. This bottom wall 31 is arranged to enter the opening 11 in the bottom of the furnace and fit tightly therein when elevated to closed position. The charge to be treated is placed on the platform 22 after which the platform is raised and the charge thereby inserted in the heating chamber.

As shown the heating chamber 10 is cylindrical in form, the axis of the cylinder being vertical. A ledge 32 of electrically fused alumina is provided around the charging opening 11 in the bottom of the heating chamber and on this ledge so as to surround the charge is a self supporting heating resistor comprising alternate horizontal bars 33 and upright rods 34. These rods and bars are made preferably of graphite and they are electrically connected together to form a continuous heating resistor extending around the wall of the heating chamber, this resistor comprising horizontal lengths 33 formed of the flat bars and vertical rods 34. The bars 33 at the lower side of the resistor rest on the ledge 32 and form supports for the resistor.

Any suitable electrical connection may be provided between the bars 33 and the rods 34 of the resistor. A very convenient electrical as well as mechanical connection between them is provided by slightly tapering the ends of the rods 34 and forming holes in the ends of the bars into which the tapered ends of the rods are forced. This form of connection is shown in Fig. 3. The tapered end of the rod 34 is inserted in the hole 35 in the bar 33 by hand and twisted slightly and at the same time forced endwise into the hole. This has been found to give a very good connection which is very inexpensive and may be easily and quickly made. The connection also facilitates the disassembly of the rods and bars for repairs. It

will be noted that the heating resistor may be easily removed from the furnace since it simply rests on the supporting ledge in the furnace. The assembly of the resistor will be carried out in the heating chamber itself to a greater or less extent, as found most convenient, free access being had to the heating chamber through the large charging opening 11 in the bottom.

10 The heating resistor is connected at each end to terminal electrodes 26 and 37 made of a suitable heat refractory material, such as graphite. These two terminal electrodes are built into the furnace wall at points adjacent each other. Preferably the connection between the ends of the heating resistor and the electrodes is similar to that provided between the rods and bars forming the resistor itself. As shown the electrodes enter 20 the heating chamber at the bottom so that their upper surfaces are substantially on a level with the upper surfaces of the bottom bars 33. Each end of the resistor terminates in an upright bar 34 and these two end bars are forced by hand into apertures provided for them in the ends of the electrodes. The electrodes will be connected to the terminals of a suitable electrical supply source by means of connections, not shown, cooperating with their outer ends.

15 Each electrode is provided with a looped or hairpin-shaped pipe 38 which is cemented in the electrode, the ends of the pipes extending from the outer ends of the electrodes. These pipes extend to points near the inside wall of the recrystallized carbon rundaum bricks lining the furnace chamber. Cooling water is circulated through the pipes whereby the bus bar connections with 25 the outer ends of the electrodes are cooled and, furthermore, the inner lining of recrystallized carbonrundaum bricks is cooled around the inner ends of the electrodes whereby short circuits are prevented. It 30 will be understood that at the extremely high temperature prevailing in the furnace the recrystallized carbonrundaum material of the lining has a comparatively low electrical resistance and as a result the electrodes would be short-circuited through the lining if this cooling means were not provided. With this water cooled arrangement operating voltages of 125 volts or more may be used.

35 55 A suitable seal is provided for the bottom of the furnace consisting of a flange 39 secured to the plate 17 around the opening 18 which fits in a channel member 40 secured to the support 23 when the platform is elevated to closed position. A suitable sealing material such as fire clay will be provided in the channel member for embedding the flange 39.

Various electrical connections may be provided for the resistor. For example, as

shown in Fig. 4, three electrodes 41, 42 and 43 may be used. These electrodes are spaced at 120 degree angles and electrically connected to the resistor at equidistant points.

While I have described my invention as embodied in concrete form and as operating in a specific manner in accordance with the provisions of the patent statutes, it should be understood that I do not limit my invention thereto since various modifications 75 thereof will suggest themselves to those skilled in the art without departing from the spirit of my invention the scope of which it set forth in the annexed claims.

What I claim as new and desire to secure by Letters Patent of the United States, is:

1. A high temperature electric furnace comprising heat refractory walls forming a heating chamber, and a heating resistor in said chamber comprising a plurality of bars of heat refractory material arranged vertically in spaced relation around the side wall of said chamber, and cross pieces joining said bars at their upper and lower ends to form a continuous heating resistor extending 25 along the side wall of said chamber and resting on the lower cross pieces.

2. A high temperature electric furnace comprising heat refractory walls forming a heating chamber, and a heat refractory electric resistor comprising a plurality of graphite bars arranged in vertical relation around said chamber, and horizontal cross pieces joining the upper and lower ends of said bars to form a continuous heating resistor, the lower cross pieces constituting the supporting means for said resistor.

3. A high temperature electric furnace comprising heat refractory walls forming a heating chamber, and a heating unit in said chamber comprising upright bars of heat refractory material and horizontal cross pieces of heat refractory material joining said bars into a continuous resistor, said cross pieces being provided with apertures, and said bars being provided with tapered ends fitting into 100 said apertures in electrical engagement therewith.

4. A high temperature electric furnace comprising heat refractory walls forming a heating chamber, a ledge extending around said chamber and integral with said walls, a heating resistor extending around said chamber resting on said ledge, said resistor comprising alternate upright and horizontal bars made of heat refractory material.

5. A high temperature electric furnace comprising heat refractory walls forming a heating chamber having a charging opening in the bottom, a ledge surrounding said opening, and a heating resistor composed of jointed bars of refractory material in said chamber supported on said ledge so that when the charge is introduced through the opening it will be surrounded by the resistor.

6. A high temperature electric furnace comprising heat refractory walls forming a heating chamber, a pair of electrodes made of heat refractory material extending 5 through the wall of said chamber at points adjacent each other, a heating resistor extending around said chamber having its ends 20 connected to said electrodes, said resistor being formed of alternate upright and horizontal bars of heat refractory material connected together to form a continuous heating resistor, the lower horizontal bars forming 25 supports for said resistor and electrical connections between said electrodes and said resistor.
7. A high temperature electric furnace 10 comprising heat refractory walls forming a heating chamber, a pair of electrodes made 15 whereby the temperature of the inner lining of the furnace is maintained sufficiently low to prevent short circuits between said electrodes.
15. A high temperature electric furnace comprising heat refractory walls forming a heating chamber, a pair of electrodes made

In witness whereof, I have hereunto set my hand this 29th day of October, 1926.

HAROLD L. WATSON.
